CLAIM

The ornamental design for the shotshell reloader actuator, as shown and described.

DESCRIPTION

FIG. 1 is a front perspective view of the shotshell reloader actuator of the present invention showing my new design;

FIG. 2 is a rear perspective view thereof; and,
FIG. 3 is a front elevational view thereof, the base of the shotshell reloader actuator of the present invention being plain and unadorned.

*Fig. 1**Fig. 2**Fig. 3*
